UNITED STATES PATENT OFFICE

CHARLES S. LENSTON, OF WORCESTER, MASSACHUSETTS, ASSIGNOR TO HOBBS MANUFACTURING COMPANY, OF WORCESTER, MASSACHUSETTS, A CORPORATION OF MASSACHUSETTS

SCORING WHEEL

Application filed September 16, 1927. Serial No. 220,004.

This invention relates to a rotary scorer for use in connection with a roll for creasing, slitting, or scoring card-board or other material of a similar kind and to the means for supporting it. This is an improvement over my application filed November 8, 1926, Serial No. 146,946.

The principal objects of the invention are to provide a mounting for the scorer in which side play is practically impossible; to provide a bearing therefor which is accessible from the side; and to provide an improved scorer for creasing purposes.

Other objects and advantages of the invention will appear hereinafter.

Reference is to be had to the accompanying drawings in which

Fig. 1 is a side view of the supporting means for the creasing or scoring wheel;

Fig. 2 is a sectional view of the same on the line 2—2 of Fig. 1;

Fig. 3 is a similar sectional view on enlarged scale; and

Fig. 4 is a central sectional view of a modified support for the scorer.

The scorer bar 10 and scoring roll 11 are of the usual construction well understood in this art. The bar is provided with a dove-tailed projection 12 extending longitudinally and the body of the scorer support 13 is secured on this dove-tail extension at any place along the bar by means of a gib 14 and holding screw 15. This fixes this body in position and it will be understood that as many of these are placed along the bar transversely as may be desired to produce the required number of creases, grooves, slits or rows of indentations in the card-board C which constitutes the work.

The support 13 is provided with a longitudinal passage or opening at the bottom extending upwardly and with side recesses 36 extending up to the center of the scorer 16 itself. Inside the longitudinal slot in the bottom of the support 13 are two plates 19 which constitute the scorer holder and have a sliding fit between the cheeks constituting the opposite sides of the passage in the support 13 for preventing side play. It is to be understood that these two plates 19, with the

scorer between them and the parts at the center thereof are pivoted on a pin 18. This holder is moved up in the opening of the support 13 about the pivot and fastened. On account of the fitting of the plates 19 against the cheeks, the scorer can have no side play.

The holder 19, consisting of these two plates, is perforated at the center to receive a bolt 21 passing through it. The head of the bolt on one end and the nut on the screw at the other are located in the side recesses 36 which extend all the way through the cheeks of the support 13 where the bolt and nut can be reached from the outside.

The scorer 16 is supported by a ball bearing 65 on this bolt. The inner race 20 of the ball bearing is wider than the outer race 20^a. It is forced, by the tightening up of the nut 22, against the inner sides of the two plates 19, constituting the holder, and fastened thereto. 70 On account of the outer race 20^a being narrower than the scorer and than the inner race, free rotation of the scorer is provided without any possibility of clamping or of jamming the outer race. The outer race of course fits 75 tightly and positively in the bore of the circular scorer 16.

The scorer itself, as shown in Figs. 2 and 3, is a circular creasing wheel. It is provided around its circumference with slanting surfaces 33 and 34, preferably made at about 30° to the plane of the scorer. These conical surfaces are not allowed to intersect each other, but the scorer is turned off to a substantially cylindrical surface 35 intersecting both, thus 85 forming a scoring surface having two oblique angles at the ends of a cylindrical surface. This scorer is shown in these figures as formed with two of these formations or circular scoring ribs.

In operation these are applied to the card-board and form two creases at a certain distance apart, which is calculated according to the character of the material to be operated upon, so that these two creases permit of 95 bending the card-board to form a right angled corner and reduce the liability of the card-board cracking anywhere along the corner.

In the form shown in Fig. 4, I have illus- 100

trated an offset wheel for scoring and slitting in which the construction is substantially the same as above described, except that the scorer is located at one side of the holder 13^a instead of in the center. In this case this holder is modified by having its opening on one side instead of through the center and the only holder is a single plate 19^a. The scorer 16^a is also offset with its edge at one side but the holding bolt 21, its nut 22 and the ball bearing are the same and apportioned in the same way to get the same results. The members 16 and 16^a are for scoring. They are of the type commonly called scoring cutters.

From this it will be seen that the scorer is so mounted as to avoid friction in the operation both at its bearing and sides and that, when it is held in position in the blade support, it is incapable of wabbling or side motion and of rubbing against the sides to introduce any friction. The specific form of creasing scorer is also a feature of importance in this invention.

Although I have illustrated and described only two forms of the invention, I am aware of the fact that other modifications can be made therein by any person skilled in the art without departing from the scope of the invention as expressed in the claims.

Therefore, I do not wish to be limited to all the details of construction herein shown and described, but what I do claim is:

1. In a supporting device for a circular scorer, the combination with a support having an opening providing opposite cheeks, a holder arranged to fit against the inner sides of the opposite cheeks, a ball bearing having an inner race just fitting in the holder and an outer race narrower than the inner race, and a circular scorer fixed to said outer race.

2. In a supporting device for a circular scorer, the combination with a support having an opening extending up from the bottom providing opposite cheeks, a holder comprising two plates arranged to fit against the inner sides of the opposite cheeks, a ball bearing having an inner race just fitting between said two plates in the holder and an outer race narrower than the inner race so as to be adapted to rotate without friction between the two plates, and a circular scorer fixed to said outer race.

3. In a ball bearing support for a circular scorer, the combination of a holder, a ball bearing having an inner race abutting at both ends against the holder and provided with an outer race thinner than the inner race to prevent rubbing and friction, and a circular scorer fixed to the outer race, the outer race being narrower than the scorer.

4. In a ball bearing support for a circular scorer, the combination of a bolt and nut, a holder through which the bolt passes and against which the nut is adapted to be tightened, a ball bearing having an inner race

abutting against the holder and provided with an outer race located within the holder and thinner than the inner race to prevent rubbing and friction, and a circular scorer fixed to the outer race, the outer race being narrower than the scorer and extending within the holder.

5. In a device of the character described, the combination with a support having an opening extending up from the bottom of a holder fitting against the opposite walls of said opening, a bolt extending through the holder, said support having recesses on its opposite sides for receiving the bolt head and its nut in accessible position, a ball bearing on the bolt, and a rotary scorer carried by the bolt.

In testimony whereof I have hereunto affixed my signature.

CHARLES S. LENSTON.
